UNITED STATES PATENT OFFICE.

MILTON C. STERN AND HERBERT E. TINNERMAN, OF DAYTON, OHIO, ASSIGNEES TO
THE EGRY REGISTER COMPANY, OF DAYTON, OHIO, A CORPORATION OF OHIO.

AUTOGRAPHIC REGISTER.

1,364,153.

Specification of Letters Patent. Patented Jan. 4, 1921.

Application filed October 29, 1917. Serial No. 199,147.

To all whom it may concern:

Be it known that we, MILTON C. STERN and HERBERT E. TINNERMAN, citizens of the United States, residing at Dayton, in the county of Montgomery and State of Ohio, have invented certain new and useful Improvements in Autographic Registers, of which the following is a specification, reference being had therein to the accompanying drawing.

This invention relates to improvements in autographic registers, which is to say, that class of registers in which one or more rolls of paper are carried over a plate forming the top of the machine and constituting a support for the paper while the clerk is writing down the amount and nature of the sale of which a record is thus to be made. When two or more sheets are used carbon paper is interposed for the purpose of making facsimile transfers of the entry to one or more sheets under the top sheet.

The object of the present invention is, in substance, twofold. This twofold idea resides in perforating the paper before it goes to the register with holes at stated or standard intervals, so that there will be a group of holes at one location and a like group further along the paper, the space between being the part to be written upon and the entries made, and in providing two sets of gripping devices, one set to enter one set of the perforations to pull or advance the paper over or through the machine and another set to enter the holes of the other set of perforations to hold the paper while the advanced section is being torn off or severed from the remainder of the paper, together with mechanism for operating these gripping devices so that the two sets of gripping devices will alternately engage with and disengage from the paper, one set at a time acting on it.

A further object of the invention is to combine with said two sets of gripping devices suitable mechanism for engaging one set with the paper and causing that set to travel from the machine so as to draw off the paper to cause the second set of gripping devices to engage the paper as the first set releases it, to cause the return of the first set to normal position and then to cause the first set to reengage the paper and the second set to disengage it.

In the accompanying drawings, Figure 1

is a perspective view of a roll of paper, partly extended from the roll, showing the groups of perforations standard distances apart; Fig. 2, a longitudinal vertical sectional view of a register showing our invention applied thereto; Fig. 3, a front elevation of the upper portion of the machine looking in the direction of the arrow in Fig. 2, showing parts of the mechanism enlarged; Fig. 4, an inverted plan view of the machine looking down upon the under side of the top and showing the distribution of the mechanism; Fig. 5, a partial sectional view and partial elevation of a portion of the top with the paper-pulling mechanism extended away from the body of the machine, the pulling set of grippers engaging the paper and the holding grippers withdrawn from the paper; Fig. 6, a like view with the pulling grippers withdrawn and the holding grippers inserted in the paper; Fig. 7, a detail view showing the holding grippers withdrawn from the paper or in non-operative position; and Fig. 8, a like view showing the holding grippers engaged with the paper or in operative position.

In Fig. 1 we have illustrated a roll of paper with a part of it run off to show the groups of perforations. Each group is composed of two sets of holes, set 2 for one set of grippers and set 3 for the other set of grippers. The groups of perforations are spaced at standard distances along the paper to leave an intermediate sheet 4 on which the clerk or store-keeper will write the entry of his sales or on which other data may be entered.

When one or more of these rolls of paper are mounted in the machine, as shown at 5, in Fig. 2, with the sheets run off over guide rolls 6 and thence along the top of the machine, with carbon paper intervening if desired, the sheets are first engaged by the pulling grippers entering the set of holes 3. These grippers then pull the sheet or sheets to the extent of what might be called a full stroke which will bring the next group of perforations near the cutter bar, whereby it may be severed, after the pulling grippers have withdrawn from their perforations and the holding grippers have entered the holes 2 of the next group of perforations.

The groups of perforations are spaced apart according to the size desired for the intermediate sheet 4.

We will now describe the devices for operating the pulling grippers. These comprise a shaft 7 mounted in the sides 8 of the machine having a hand crank 9 to rotate it. 5 The shaft carries a gear wheel 10 which meshes with a rack 11 mounted on a slide 12. The rack is mounted in suitable ways or guides 13 on the under side of the slide. The slide in turn is mounted in guides or ways 10 13^a secured to the lower side of the top. By turning the crank the slide 12 will be made to extend out beyond the machine, as shown in Fig. 5. In doing so it carries the paper with it by means of the pulling grippers 14 15 which are in the nature of pins mounted in the head piece 15 of the slide and adapted to be projected upward through the perforations in the paper and to be drawn downward to release the paper. For so operating 20 these gripper pins we provide crank arms 16 connected to pins 14 through links 14^a the arms 16 being secured to a rockshaft 17 mounted in bearings 18 carried by the slide. In the rockshaft is secured an operating 25 arm 19 which connects by a rod 20 with the bracket 21 on the rack bar 11. A stop 22 on the slide 12 is engaged by the end of the rack bar, so that when the bar is advanced it will carry the slide 12 with it. When the 30 slide has been advanced until the hook 23 strikes the stop 24, (see Fig. 4), the paper will have been drawn out far enough to bring a set of holes in the next group of perforations (Fig. 1) in line with the holding 35 grippers. When this occurs a reverse movement of the crank will start the rack bar inward. It will slide away from the stop 22 (Fig. 5) without moving the slide 12, until the contact bar 25, secured to the 40 rockshaft 17, contacts with the slide 12. This gives the rod 20 and operating arm 19 a direct pull on the slide so that when the rack is run back into the machine it carries with it the slide 12. The short movement of 45 the rack between the time it disengages the stop 22 and the contact bar engages the slide 12 operates to withdraw the gripping pins 14 from the extended paper.

The positions of these parts just described 50 are seen in Figs. 5 and 6. In the former with the rack bar in contact with the stop 22 and the gripping pins extended through the perforations and in the latter figure with the rack bar moved off from the stop 22 and 55 the contact bar 25 moved against the slide 12 with the contact pins withdrawn from the paper. In the relation of the parts shown in Fig. 6 the rack and slide are returned to normal position with respect to 60 the machine and the paper is left hanging down.

When the head 15 reaches the machine the user takes hold of the now hanging paper and tears it off against the tearing or cutting edge 15^a of a guide bar 16^a pivoted to

the machine at 17^a and held at the other end by a suitable fastening, as a bolt and thumb nut 18^a. During this operation the holding pins are in engagement with the paper by extending through their perforations, as 70 will presently appear. And it will be understood also that the extended pull given the paper when the slide and rack moved out to the limit brought the paper in such position that the perforations in group 3 would register with the position of the gripping pins 14 after the head 15 has been returned home to the machine, as above described.

Referring now to the holding grippers they comprise two pins 26 mounted to slide 80 up and down in the top 27 and across the space between the top and the paper guide bar 27^a, which extends across the top of the machine and may be removably secured in any convenient manner. There is one 85 pin, 26, at each side of the slide 12, as shown more clearly in Fig. 4. These pins are operated up and down by means of a tilting frame 28 pivoted at 29 on a bracket 30 depending from the top. When these 90 frames are tilted on the pivot 29 they insert the pins into the perforations 2 or withdraw them therefrom. During the outward movement of the slide, when the gripping pins are pulling the paper, the holding pins 95 are withdrawn and the frames 28 are tilted, as shown in Fig. 7. They are normally held in this position by the spring 31 secured at one end to the bracket 32 and at the other on a pin 37 on the frame 28, the 100 line of strain being below the axis 29. Such is the position of these parts when the gripping pins are moving outward with the paper. At the time the outward stroke of the slide is finished certain tripping devices 105 carried by the rack bar will have moved to the position shown in Fig. 7, ready on the return stroke of the rack to trip the frame 28 from the position shown in Fig. 7 to that shown in Fig. 8. These tripping devices 110 consist of a rod 33 (Fig. 4) secured to the rack bar 11 and having journaled on each end a plate or by pass pawl 34 and each having a cam 35 adapted on the commencement of the return stroke to contact with the 115 tripping pin 36 on the frame 28 to throw the frame from the position shown in Fig. 7 to that shown in Fig. 8, and thereby insert the holding grippers or pins into the paper perforations. This takes place just 120 as the gripping pins are withdrawn so that as the one set of pins lets go of the paper the other set engages the paper.

The holding pins or grippers remain engaged with the paper, as before stated, 125 until the slide and rack have been fully returned and the paper torn off at the edge 15^a of the head 15. Then when the next out stroke is started the holding pins or grippers are withdrawn from the paper by 130

the action of the contact bar 25 in tripping the frames 28. This bar at that time stands over the other tripping pins 37 on the frames 28, (see Fig. 4). The first movement outward of the rack, until it strikes the stop 22, causes the contact bar to swing downward and engage these tripping pins 37. In this way the holding pins or grippers are withdrawn from the paper before there is an actual movement of the slide 12 because the slide does not start to move until the rack has traveled up to and against the stop 22.

Referring again to the tripping devices 29, 34 and 35 it will be understood that when the cams 35 reach the pins 36, when the latter are in the position shown in Fig. 7, the cams have to ride past those pins in order to be ready on the return stroke of the rack to engage said pins and trip the frames 28 to throw the holding pins into the paper. To enable the cams 35 to pass the pins 36 the plates 34 are loosely journaled on the rod 29 so that the cams 35 when they contact with the pins 36 spring down, slide against and past the pins and then move up to their position shown in Fig. 7. To cause the plate 34 to so return the cams an arm 38 is secured to the rod 29 rigidly, while the spring 39 on a stud 40 on the plate 34 extends to the arm 38 and thereby makes a spring connection between the plate 34 and the rod 29. A small stop 41 on the plate 34 abuts the arm 38 and limits the swinging or rotary movement of the plate on the rod so that the cam 35 will stop at the right place on its return movement after springing past the pin 36.

In order to normally keep the pulling pins or grippers extended through the paper and the holding pins normally withdrawn from the paper a spring is employed to keep the rack bar 11 in contact with the stop 22, in which position the contact bar stands immediately over the pins 42 on the tilting frames 28. By preference this spring is in the form of a coil, as shown at 43, and is placed about the shaft 7 secured at one end to the frame, as shown at 44, and at the other to the shaft, as shown at the screw 45. The normal tendency of this spring is to urge the rack bar 11 against the stop 22.

It will be seen from the foregoing that the paper, through the instrumentality of the pulling pins or grippers, is taken hold of and advanced successively as required, is released by such pins or grippers and at the same time engaged by the holding pins or grippers during the return of the pulling pins or grippers, until the paper is torn off and released by the holding pins or grippers just as the paper is reengaged by the pulling pins or grippers. It will be seen also that by reason of the fixed distances between the groups of perforations the paper

is advanced each time the distance incident to the size of the sheet to be used for recording the sale or entry.

We have described that type of detail mechanism which we deem preferable and which in practice has proved efficient and successful, but we desire to be understood as not limiting ourselves to such details as they may, in fact, be modified in construction and arrangement while still carrying out the essentials of the invention.

Having thus fully described our invention, what we claim as new and desire to secure by Letters Patent, is:—

1. In an autographic register, the combination, with a series of holding pins adapted to enter perforations arranged in groups and regularly spaced apart in a web of paper movable over said pins, also a series of pulling pins adapted to enter perforations in said paper, a plurality of means to actuate said holding and pulling pins to alternately engage and release the paper, and mechanism to impart advance and return movements to the pulling pins. 90

2. In an autographic register, the combination, with a series of holding pins carried by swinging frames, and a series of pulling pins carried by arms extending from a rockshaft, of mechanism to actuate the holding pins comprising a cam and an actuating bar to tilt the frames first one way and then the other, mechanism to actuate the pulling pins comprising a rockshaft with crank arms, a slide on which the pulling pins and rockshaft are mounted, a rack bar connected with the rockshaft adapted to actuate the slide but having limited independent movement, the cams for actuating the tilting frames being carried by the rack bar and the contact bar being carried by the slide. 100

3. In a register, an actuating gear, a rack meshing therewith, a slide on which the rack is movably mounted, a stop to limit the movement of the rack with respect to the slide, pulling pins, and a rockshaft connected to the pins mounted on the head of the slide, a connection between the rockshaft and the rack to operate the pins when the rack moves independently of the slide in one direction, and an actuating bar connected with the rockshaft to limit the other movement of the rack with respect to the slide in the other direction, whereby the rack operates the slide in both directions and operates the pins in and out of engagement with the paper, holding pins mounted in the top of the machine, tilting frames connected with said pins, springs to hold the frames in adjusted positions, and cams carried by the rack and adapted to swing the frames to throw the pins into engagement with the paper. 115

4. In an autographic register, a slide hav- 130

- ing a head against which to tear off portions of a perforated paper web movable thereover, pulling pins adapted to engage said perforations, a rock shaft mounted on 5 the head, a rack bar mounted on the slide and having limited movement independently of the slide, a connection between the rack bar and the rock shaft to operate the latter by the independent movement of the 10 rack, a contact bar mounted on said rock shaft, and a part of said slide adapted to be engaged by said rack to cause the rack to move the slide.
5. In an autographic register, a holding 15 pin, a swinging frame controlling the holding pin and adapted to project said pin through or withdraw it from perforations in a web of paper movable thereover, and devices adapted to travel relative to the 20 frame to tip it back and forth to operate the pin.

6. In an autographic register, a holding pin, a tilting frame secured thereto, projections from the frame, a traveling cam adapted to tip the frame by contact with 25 one of the projections, a contact bar adapted to reversely tip the frame by contact with the other of the projections, and a spring acting on the frame to hold it in either position.

7. In an autographic register, a holding pin adapted to engage and release a paper web movable thereover, a pivoted frame controlling the holding pin and movable to either of two positions to cause said pin to 35 engage or disengage the paper web, and a spring connected with the frame and adapted to hold it in either position.

In testimony whereof, we affix our signatures.

MILTON C. STERN.
HERBERT E. TINNERMAN.
